UNITED STATES PATENT OFFICE.

JOHN W. BROWN, OF FORT WAYNE, INDIANA.

CARBURETOR ATTACHMENT.

Application filed December 24, 1920. Serial No. 432,891.

To all whom it may concern:

Be it known that I, JOHN W. BROWN, a citizen of the United States of America, and resident of Fort Wayne, in the county of 5 Allen and State of Indiana, have invented certain new and useful Improvements in Carburetor Attachments, of which the following is a specification.

This invention relates to improvements in 10 carburetor attachments for hydrocarbon engines and the objects thereof are; first, to provide a trap adapted to be positioned between the carburetor and the intake pipe of the engine constructed so as to receive and 15 detain any condensations or liquid fuel that may collect in the intake pipe and tend to drain back in the carburetor; and second, to introduce heated air into the trap in a manner so as to vaporize the liquid content of 20 the trap and cause it to pass into the intake pipe and intermix with the fuel passing from the carburetor through the intake pipe to the engine.

The objects of the improvement are ac- 25 complished by the construction illustrated in the accompanying drawings in which:

Fig. 1 is a side elevation showing an assembly of a carburetor, intake pipe and exhaust manifold of usual construction, and 30 including the invention arranged in connection therewith, there being parts cut away and in section;

Fig. 2 is a front end view of the trap, shown partly broken away and in section; 35 and

Fig. 3 is an elevation of Fig. 1 showing a central section thereof in a plane at right angles thereto.

Similar characters of reference indicate 40 corresponding parts throughout the several views and referring now to the same:

1 is a block having a central opening 2 extending therethrough, and having in its lower portion a cavity 3 which has communication with the opening 2 through a series of perforations 4, there being a depression 5 in the block extending transversely in its wall at the lower side of the opening 2 coincident with the upper ends of the perforations 4. The block has also a threaded opening 6 in its bottom communicating with the cavity 3, and into the opening is secured a pipe elbow 7 having connection with an air pipe 8 hereinafter referred to.

55 The block 1 is secured in position between the carburetor 9 at its outlet port and the

intake pipe 10 at its receiving end, and the air pipe 8 is shaped to fit over the exhaust manifold 11 so as to rest in contact with the top thereof and become heated thereby. The 60 pipe 8 has at its upper end a valve 12 by means of which the admission of air into the pipe may be regulated. It is preferable, when the invention is applied to an automobile, that the pipe extends through the dash 65 or instrument board 13 of the automobile so that the valve may be manipulated by the operator from the driver's seat.

The carburetor 9 herein shown has a throttle valve 14 in its outlet port by which the 70 supply of fuel from the carburetor to the engine is regulated in the usual manner, the carburetor being of any suitable type.

In the operation of the invention any liquid fuel that may become deposited by condensation or otherwise within the intake pipe and tend to pass back toward the carburetor will drain through the perforations 4 into the cavity 3 instead of entering the carburetor and causing it to become flooded. 75 Usually in starting the engine while it is cold, the fuel drawn from the carburetor through the intake pipe to the engine tends to condense and accumulate therein, causing difficulty during the initial operation of the 80 engine. However, by use of the present invention the condensed fuel drains from the intake pipe into the trap, thus relieving the engine of becoming choked by an overcharge of liquid in the fuel mixture. When 85 the engine is in operation the air pipe 8 becomes heated through contact with the exhaust manifold of the engine, and as air is admitted into the pipe 8 through the valve 12 it becomes heated in its passage there- 90 through and enters the cavity 3 causing the liquid fuel which had previously drained thereinto to vaporize and pass through the perforations 4 into the opening 2 in the block 1 so that it becomes mixed with the fuel passing from the carburetor into the intake pipe. The hot air thus admitted through the trap into the path of the fuel entering the engine has the effect of expelling the content of the trap as well as tending 95 to vaporize any liquid in the fuel passing from the carburetor to the engine and thus enhancing the explosiveness of the fuel.

A further advantage of the invention, especially when applied to an automobile, is that with its use the carburetor may be initially adjusted to insure the admission of

ample gasoline as will aid in starting the engine, and after which the fuel may be reduced to a proper consistency for higher engine velocities by the admission of additional air into the fuel mixture, the regulation of which is accomplished by the operator from the driver's seat. In this manner the fuel admitted to the engine may be readily proportioned in its contents of air and gasoline, as various operating conditions may require, to attain its maximum efficiency.

What I claim is:—

1. In an attachment for a hydrocarbon engine including a carburetor and intake pipe; a trap adapted to be positioned between the carburetor and intake pipe, said trap having a fuel opening extending therethrough from the carburetor to the intake pipe, there being also a cavity formed in the trap and a series of perforations leading from the cavity into said opening; and

means for the admission of air into the cavity.

2. In an attachment for a hydrocarbon engine including a carburetor and intake pipe, a trap adapted to be positioned between the carburetor and intake pipe, said trap having an opening extending therethrough for the passage of fuel from the carburetor into the intake pipe, there being a transverse depression continuous with the opening at the lower portion thereof, there being also a cavity formed in the trap beneath said depression, and a series of perforations affording communication between the cavity and depression, said cavity having an inlet opening for the admission of air. 35

In testimony whereof I affix my signature, in presence of two witnesses.

JOHN W. BROWN.
